SPLICING TOOL

David C. Hubbard, Centralia, Mo., assignor to
 A. B. Chance Company, Centralia, Mo., a corporation of Missouri

Application July 1, 1940, Serial No. 343,459

8 Claims. (Cl. 140—113)

The present invention relates to splicing tools and is particularly concerned with splicing tools of the type adapted to be used in splicing live electric lines.

One of the objects of the invention is the provision of an improved splicing tool which is adapted to be used with automatic sleeve splices for the purpose of splicing energized electric wires.

Another object of the invention is the provision of an improved tool of the class described which is adjustable to allow for the various sizes of automatic splices and which permits the setting of the tool at an angle to the insulating pole with which it is handled.

Another object of the invention is the provision of an improved splicing tool of the class described which is provided with separate gripping means for positively preventing the automatic splice member from sliding endwise out of the tool and with self-aligning jaws to permit the jaws to align themselves to the shape of the automatic sleeve splice.

Another object of the invention is the provision of an improved splicing tool by means of which energized electric wires may be handled and spliced while the tool and wires are handled by means of elongated insulating poles.

Another object of the invention is the provision of an improved splicing tool of the class described which is simple, sturdy, capable of economical manufacture and adapted to perform its functions for a long period of time without necessity for repair or replacement.

Other objects and advantages of the invention will be apparent from the following description and the accompanying drawings, in which similar characters of reference indicate similar parts throughout the several views.

Referring to the three sheets of drawings accompanying this specification,

Figure 1 is a view in perspective of an energized high tension electric conductor which is believed spliced by means of a tool embodying the invention;

Figure 2 is a top plan view of the splicing tool constructed according to the invention;

Figure 3 is a side elevational view of a splicing tool;

Figure 4 is a rear elevational view of the splicing tool;

Figure 5 is a vertical sectional view taken on the plane of the line 5—5 of Figure 4 looking in the direction of the arrows;

Figure 6 is a vertical sectional view taken on

the plane of the line 6—6 of Figure 3 looking in the direction of the arrows;

Figure 7 is a vertical sectional view taken on the plane of the line 7—7 of Figure 3 looking in the direction of the arrows; and

Figure 8 is a fragmentary end view of the tool showing the bell-mouthed opening at the right in Figure 3.

Referring to Fig. 1, 10 indicates in its entirety the improved splicing tool constructed according to the invention which is shown in connection with an automatic splice 11 and the two ends 12 and 13 of an energized high tension electric conductor. 14 indicates a clamp stick of the type having an elongated insulating wooden pole 15 provided with an insulating sleeve 16 at the top and with a clamping head 17 which may have a hook or a pair of jaws adapted to clamp the electric conductor 13 so that it may be handled although located at a distance from the lineman.

The automatic splice 11 is of the type which is adapted to effect a tight electrical and mechanical connection between the conductors 12 and 13 when they have been pushed into the apertures in the opposite ends of the automatic splice 11.

It should be understood that both the clamp stick 14 and the splicing tool 10 may be mounted on elongated wooden insulating poles, such as, for example, from 6 to 16 feet in length. Part 30 of this length is rendered necessary by the high tension electricity with which conductors 12 and 13 may be energized, while additional length of the poles may be necessary for reaching the point of the splice from the position of the lineman on a transmission line pole.

The tool 10 is preferably mounted on a wooden pole 18 provided with a cap 19 having a supporting flange 20 that is provided with a plurality of grooves 21 and teeth 22 for engagement with complementary grooves and teeth on the supporting flange 23, which is carried by the tool.

A thumb screw 25, provided with a shank 24, passes through the slot 35 in the flange 23, and is threaded into an aperture in the flange 20 to secure the tool to the supporting pole 18 in any of a multiplicity of angular positions. This enables the operator to reach a splicing position and to control the tool although the operator may be located in any of a multiplicity of different positions with respect to the splice.

The splicing tool 10 preferably includes a supporting body 30 which is provided with a vertically extending flange 31 and a substantially cylindrical body portion 32 which is provided with an axially extending threaded aperture 33. This

aperture 33 is adapted to receive the threaded shank 34 which is carried by the toothed flange 23 previously mentioned. The toothed flange 23 is preferably provided with a slot 35 which extends axially of the threaded shank 34.

Vertically extending flange 31 may be provided with a flat guide surface 35 on its inner side for engaging complementary guide surfaces 36 on the sliding cam 37. The cam 37 comprises a metal body which may be provided with a lower flat surface 38 and with an axially extending cylindrical guide member 39.

The cylindrical guide member 39 is slidably engaged in a cylindrical bore 40 in the threaded shank 34, which bore is of greater length than the guide member 39. A metal washer 41 may be mounted on the guide member 39 and interposed between the surface 38 and the end 42 of the screw bolt 34.

In order to secure a minimum of friction between the sliding surfaces 36 and 35, the cam member 37 may be provided with a plurality of guide ribs 43 on its right side (Fig. 6) which ribs carry the surfaces 36.

The cam member 37 is substantially triangular when viewed in elevation from the side of the cam, as shown in Figure 4, and it is provided with the inclined camming surface 44 at its upper end. This camming surface is adapted to engage the curved or ball-shaped surface 45 on the lower end of one of the clamping levers 46, the other lever being indicated at 47.

The two clamping levers 46 and 47 may be identical in structure at their upper ends, but different in structure at their lower ends. For example, the clamping lever 47 is provided with a pair of laterally projecting pivot ears, or flanges, 48 at its lower end between which the curved body portion 49 of the other clamping lever 46 is received.

A metal pintle 50 passes through registering apertures 51 in the flanges 48, 48 and body 49 and is riveted over at each end in such manner as to support the clamping lever 46 pivotally on the clamping lever 47.

The partially spherical surface 45 on the lower end of clamping lever 46 has already been described. It is located below the pintle 50 in such manner that outward pressure on this partially spherical surface 45 causes the levers to pivot toward each other.

The clamping lever 47 differs from lever 46 also, in that at its lower end, clamping lever 47 is provided with a vertically extending flange 52 which may have a circular outer boundary and which is provided with a centrally located aperture 53.

This aperture is adapted to receive an integral threaded stud 54 which is carried by the vertical flange 31 of the supporting body 30. Supporting body 30 may have a flat surface 55 surrounding the threaded stud 54 except for the formation of one radially extending rib 56.

Depending flange 52 has its inner face 57 formed with a plurality of teeth 58 separated by the grooves 59 which are complementary to the shape of the rib 56. A wing nut 60 threaded on the stud 54 is adapted to clamp the flange 52 against the flat surface 55 with rib 56 in one of the grooves 59.

A plurality of the grooves 59 being provided, the clamping jaws 46, 47 may be supported at any of a multiplicity of predetermined angles on the body 30. Each of the clamping levers 46

and 47 is preferably provided with an upwardly extending elongated arm 61 which extends diagonally outward from the pintle 50 in such manner that a pair of clamping members 62, 63 (Fig. 2) may be supported at the top of these levers. That is, the two levers 46 and 47 have a spread at the top.

Closely above the pintle 50, each lever is provided with cylindrical sockets 64, 65, these two 10 sockets receiving the ends of a helical coil spring 66 which is under a predetermined compression and adapted to spread the levers 46 and 47 apart. Spring 66 also keeps the partially spherical surface 45 in engagement with the cam surface 44 15 as the cam resists the spreading of the levers.

At the upper end of each of the levers 46 and 47, each lever is provided with an enlarged aperture 67 and 68 and the apertures 67 and 68 are in substantial alignment with each other when 20 the parts are in the position of Figure 6. The upper end of each lever may be provided with a flat surface 69, 70, except that one corner is preferably cut away and formed with a lower flat surface 71 and an inclined surface 72.

25 These two surfaces 71, 72 form stop surfaces for engaging a laterally projecting lug 73 (Fig. 3) carried by each of the clamping members 62, 63. The two clamping members 62, 63 are similar in construction but differently formed for the 30 right and the left-hand side on account of the fact that the lugs 73 are both located at the top and they extend in opposite directions.

The clamping members 62, 63 are otherwise 35 similar in construction so that only one of them need be described in detail. For example, clamping member 62 is provided with a main body 74 which is an elongated trough-shaped member when viewed from the inside. The body 74 has on its interior the tapered trough 75 which is 40 complementary in shape to part of the outer surface of an automatic splice 11.

The trough 75 tapers like the end of the automatic splice 11 but is large enough so that it may be used to engage splices of different size. 45 At its right end (Fig. 5) the trough tapers to a relatively small groove 76. At its left-hand end (Fig. 5) the trough enlarges to a bell-shaped opening 77 which is slightly larger than any splice 11 with which it will engage.

50 The main body 74 of each clamping member supports the half frusto-conical mouth member 78 which is integrally joined to the body 74 and communicates therewith through the groove 76. Each frusto-conical mouth member 78 is provided with a laterally extending lip 79 which overlaps the frusto-conical formation on the other clamping member in such manner that the clamping members may be separated but the conical formations will still be closed by means of these 55 overlapping portions 79.

Referring to Fig. 8, the upper lip 79 is curved on the radius of the pivot 50, but the lower lip 79 extends tangentially. This permits close cooperation between the flanges 79 and the adjacent edges of the two half frusto-conical members 78 in any 60 position of the parts.

The overlapping portions 79 extend from a shoulder 80 and are located on the opposite edges of the two half frusto-conical members 78 so that 65 there is an overlapping flange above, and an overlapping flange 79 below, as shown in Figure 1.

When the two clamping members 62 and 63 are 70 arranged as shown in Figure 6, the grooves 76 form

a through-aperture indicated at 81 in Figure 6. Each of the bodies 74 of the clamping members 62 and 63 is provided with a threaded aperture 82 at the left end of the trough 75 (Fig. 5) which has in it a set screw 83 provided on its inner end with a relatively sharp circular rib 84. At its outer end each set screw has a kerf 85 (Fig. 3) for receiving a screw driver or other tool.

The outer surface of each of the bodies 74 is substantially flat at 86 (Fig. 3) surrounding the set screw 83 and at an intermediate point the outer surface of each clamping member is angular, being formed by two diagonally extending surfaces 87, 88 intersecting to form a ridge 89.

The upper end of each lever 46, 47 is also formed with a complementary V-shaped groove 90 for receiving these triangular ridges 87-89 on the clamping members. The V-shaped groove 90 traverses the inner surface of each of the levers 46, 47 at the apertures 67.

Centrally located of the body 74 and centrally located between the ends of the triangular ribs 87-89, there is a laterally projecting integral threaded stud 91 on each clamping member 62 or 63. This stud 91 passes through the enlarged aperture 67 and carries the nut 92.

Interposed between the nut 92 and a flat surface 93 on the outside of each lever 46 or 47 there is a relatively heavy spring washer 94. The nuts 92 are purposely left loose so that the spring washers 94 are only slightly compressed. Due to the enlarged apertures 67 surrounding the threaded studs 91 and due to the resilient clamping action of the nuts 92 and spring washers 94, each clamping member is permitted a limited degree of universal movement on its supporting lever. This movement is mainly about an axis which is at right angles to the longitudinal axis of the clamping members.

The lug 73 and stop surfaces 71, 72 limit the pivotal movement of each clamping member on its lever and hold them in such position that the flanges 79 overlap portions of the half frustoconical members.

Thus, when the device is assembled, as shown in Fig. 1, it is formed with a means at the left end for clamping the automatic splice 11 and with a bell-shaped opening at the right end leading to an aperture 81 for receiving the wire 13, which is to be joined to the splice 11.

The method of operation and mode of use of my splicing tool is as follows: The wire 12 may first be grasped by means of the clamp stick 14, and the automatic splice may be secured in the tool 10 by locating it between the clamping members 62, 63, which are brought into clamping engagement with the automatic splice by turning the threaded shank 34 by means of the pole 18. The turning of the pole 18 elevates the cam 37 and forces the partially spherical formation 45 outward to such a degree that the clamping members 62 and 63 come together and engage the automatic splice 11.

Spring washers 94 permit a limited universal movement between the clamping members and their supporting levers 46 and 47, and permit a better fit between the clamping members 62 and 63 and splices of various sizes.

The size range of the splices is considerable, and that of the tapered ends of the splice is in proportion to the variation in size. Rigidly mounted clamping members cannot be depended upon to seat properly on all sizes of splice, but the limited universal movement of the clamping

members on the levers provides for a proper seating or fit between the tool and the splice.

The larger the splice, the farther apart the edges 96, 97 are from the offset 80. The flanges 79 then serve as guides, supplementing the frustoconical members 78.

It is found, however, that if the screw 34 and cam 37 are relied on alone to effect a tight clamping action between the clamping members 10 and the splice, there is a tendency for the screw to bind, and it becomes difficult to release the splice, due to the binding action on the end of the screw 34. This binding action is reduced by means of the washer 41, and the gripping action 15 of the clamping members is supplemented by means of the set screws 83.

These set screws preferably do not engage the splice until it is gripped snugly, but not too firmly, by the clamping members 62, 63. Then the 20 set screws may be turned to engage the splice with sufficient firmness to bite into the splice slightly.

The annular ridge at the end of the screws permits the rotation of the screws, and causes them 25 to bite into the splice and grip it more firmly with less pressure on the cam 37, and the thrust washer 41, so that the tool may easily be removed.

This procedure is not necessary in every embodiment of the tool; but, if followed, it makes the tool operate more easily. When the automatic splice has been secured to the wire 12, then the tool may be removed from the left end of the splice 11 and placed on the right end of the 35 splice 11, as shown in Fig. 1, to be used for the attachment of the wire 13 for the splice 11.

The grip of the set screws, which are again applied after the clamping members are brought into clamping engagement, provide a purchase 40 on the splice, which is firm enough to prevent the splice from sliding endwise out of the tool when the conductor is forced into the splice. A reverse torque on the pole 18 is, of course, applied to withdraw the screw 34 and remove the clamping members 45 from the splice, and this would have to be resisted by the rigidity of the conductors, to which the clamping members are applied.

There is very little rigidity to such conductors, particularly when only one, such as the conductor 12, is attached to the tool by means of the splice 11. Therefore, it is highly desirable that the friction involved in the release of the tool be as little as possible.

After the tool has been secured to the splice 11, as shown in Fig. 1, and the set screws 83 have been tightened to give it a better grip, the wire 13 is forced into the automatic splice 11; and thereafter the tool is removed by rotating the pole 18 counter-clockwise, and the clamp stick 14 may also be removed. The clamping members of the splicing tool are self-opening, due to the action of the spring 66, and the rotation of the threaded member 34 permits the cam to move downward so that the levers are forced apart by the spring 66.

At this time the relation of the automatic splice 11 and tool 10 with respect to the wire 12 may be the same as it is illustrated in Fig. 1 with respect to the wire 13. That is, the tool may be turned around on the splice and may have its bell-shaped opening turned toward the wire 12 so that the wire 12 is inserted into the bell-shaped opening and into the aperture 81, which leads to the aperture in the splice 11.

Once the splice 11 is secured on the wire 12, the

tool 10 may be turned around and secured to the other end of the splice 11, as shown in Fig. 1.

When the cam 37 is driven upward by screw 34, it causes the lever 46 to pivot clockwise with respect to lever 47, which may be considered fixed. The partially universal mounting of the clamping members 62 and 73 on these levers permits the clamping members to align themselves with the splice 11. It does not matter which end of the clamping members comes together first, because in either event the set screws 83 must be so adjusted that they will engage and clamp the splice when the edges 96, 97 of the conical formations engage the offsets 80 of these conical members. At that time the overlapping portions 79 are overlapped outside the adjacent conical formations.

Prior to the invention of the present tool, the connecting of such an automatic splice to the loose wire or wires was extremely difficult, being similar to the threading of a needle at arm's length.

The present splicing tool greatly simplifies the making of hot line splices, and the wire is easily guided into the bell-mounted opening of the tool by means of a clamp stick while the conductors to be spliced are pulled tight with rope blocks, which are themselves insulated, with link sticks. One or both ends of the conductor may be attached to the automatic splice in this manner, thus making it possible to do a complete splicing job without interrupting the service in any way.

It should be noted that the cam surface 44 tapers toward the top and that as the supporting flange 52 is rotated on stud 54 the cam 37 is still in position to force the two levers together. The cam 37 operates on the levers irrespective of the angular position of the levers 46, 47 with respect to the body 30 or the pole which carries the complete assembly.

The adjustable jaws or set screws 83 positively prevent the automatic splice from sliding endwise out of the tool when the tool is fully closed. The tool is adjustable for various sizes of splices, and it has a second adjustable feature which permits the splice head to be set at an angle to the tightening or operating screw 34. The clamping members of the tool are self-aligning, due to the spring action between the clamping members and their supporting levers.

It will thus be observed that I have invented an improved splicing tool, by means of which much of the time lost according to the methods of the prior art is eliminated and much labor saved. Costly service interruptions may be wholly eliminated when the present splicing tool is used, and the transmission lines may be repaired with the highest degree of efficiency.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a splicing tool, the combination of a supporting body provided with a pair of levers movably mounted with respect to each other, actuating means carried by said bodies for selectively moving said levers in either direction toward or from each other, clamping means carried by said

levers for clamping a splicing member between said levers, and a bell-shaped guiding member carried by said clamping means for guiding a conductor into said splicing member.

- 5 2. In a splicing tool, the combination of a supporting body provided with a pair of levers movably mounted with respect to each other, actuating means carried by said bodies for selectively moving said levers in either direction toward or from each other, clamping means carried by said levers for clamping a splicing member between said levers, and a bell-shaped guiding member carried by said clamping means for guiding a conductor into said splicing member, said clamping members being mounted for limited universal movement on said levers.
- 10 3. In a splicing tool, the combination of a supporting body provided with a pair of levers movably mounted with respect to each other, actuating means carried by said bodies for selectively moving said levers in either direction toward or from each other, clamping means carried by said levers for clamping a splicing member between said levers, and a bell-shaped guiding member carried by said clamping means for guiding a conductor into said splicing member, said clamping members being provided with adjustable threaded jaws whereby the clamping members may be brought into tight engagement with splicing members of different size when the clamping members are closed against each other.
- 15 4. In a splicing tool, the combination of a pair of opposed metallic members, said metallic members being formed with opposing grooves of a size adapted to form an aperture for passing the conductor to be spliced, said grooves communicating on one side with a trough in each clamping member and communicating on the other side with a tapered trough-like formation in each clamping member adapted to form a funnel leading to said opening.
- 20 5. In a splicing tool, the combination of a pair of opposed metallic members, said metallic members being formed with opposing grooves of a size adapted to form an aperture for passing the conductor to be spliced, said grooves communicating on one side with a trough in each clamping member and communicating on the other side with a tapered trough-like formation in each clamping member adapted to form a funnel leading to said opening, said latter trough-like formations being substantially half-frusto-conical.
- 25 6. In a splicing tool, the combination of a pair of opposed metallic members, said metallic members being formed with opposing grooves of a size adapted to form an aperture for passing the conductor to be spliced, said grooves communicating on one side with a trough in each clamping member and communicating on the other side with a tapered trough-like formation in each clamping member adapted to form a funnel leading to said opening, said latter trough-like formations being substantially half-frusto-conical and being provided with overlapping flanges extending from an offset portion whereby the funnel is maintained closed when the clamping members are spread apart to engage a larger splicing member.
- 30 7. In a splicing tool, the combination of a pair of opposed metallic members, said metallic members being formed with opposing grooves of a size adapted to form an aperture for passing the
- 35 8. In a splicing tool, the combination of a pair of opposed metallic members, said metallic members being formed with opposing grooves of a size adapted to form an aperture for passing the conductor to be spliced, said grooves communicating on one side with a trough in each clamping member and communicating on the other side with a tapered trough-like formation in each clamping member adapted to form a funnel leading to said opening, said latter trough-like formations being substantially half-frusto-conical.
- 40 9. In a splicing tool, the combination of a pair of opposed metallic members, said metallic members being formed with opposing grooves of a size adapted to form an aperture for passing the conductor to be spliced, said grooves communicating on one side with a trough in each clamping member and communicating on the other side with a tapered trough-like formation in each clamping member adapted to form a funnel leading to said opening, said latter trough-like formations being substantially half-frusto-conical and being provided with overlapping flanges extending from an offset portion whereby the funnel is maintained closed when the clamping members are spread apart to engage a larger splicing member.
- 45 10. In a splicing tool, the combination of a pair of opposed metallic members, said metallic members being formed with opposing grooves of a size adapted to form an aperture for passing the conductor to be spliced, said grooves communicating on one side with a trough in each clamping member and communicating on the other side with a tapered trough-like formation in each clamping member adapted to form a funnel leading to said opening, said latter trough-like formations being substantially half-frusto-conical and being provided with overlapping flanges extending from an offset portion whereby the funnel is maintained closed when the clamping members are spread apart to engage a larger splicing member.
- 50 11. In a splicing tool, the combination of a pair of opposed metallic members, said metallic members being formed with opposing grooves of a size adapted to form an aperture for passing the conductor to be spliced, said grooves communicating on one side with a trough in each clamping member and communicating on the other side with a tapered trough-like formation in each clamping member adapted to form a funnel leading to said opening, said latter trough-like formations being substantially half-frusto-conical and being provided with overlapping flanges extending from an offset portion whereby the funnel is maintained closed when the clamping members are spread apart to engage a larger splicing member.
- 55 12. In a splicing tool, the combination of a pair of opposed metallic members, said metallic members being formed with opposing grooves of a size adapted to form an aperture for passing the conductor to be spliced, said grooves communicating on one side with a trough in each clamping member and communicating on the other side with a tapered trough-like formation in each clamping member adapted to form a funnel leading to said opening, said latter trough-like formations being substantially half-frusto-conical and being provided with overlapping flanges extending from an offset portion whereby the funnel is maintained closed when the clamping members are spread apart to engage a larger splicing member.
- 60 13. In a splicing tool, the combination of a pair of opposed metallic members, said metallic members being formed with opposing grooves of a size adapted to form an aperture for passing the conductor to be spliced, said grooves communicating on one side with a trough in each clamping member and communicating on the other side with a tapered trough-like formation in each clamping member adapted to form a funnel leading to said opening, said latter trough-like formations being substantially half-frusto-conical and being provided with overlapping flanges extending from an offset portion whereby the funnel is maintained closed when the clamping members are spread apart to engage a larger splicing member.
- 65 14. In a splicing tool, the combination of a pair of opposed metallic members, said metallic members being formed with opposing grooves of a size adapted to form an aperture for passing the conductor to be spliced, said grooves communicating on one side with a trough in each clamping member and communicating on the other side with a tapered trough-like formation in each clamping member adapted to form a funnel leading to said opening, said latter trough-like formations being substantially half-frusto-conical and being provided with overlapping flanges extending from an offset portion whereby the funnel is maintained closed when the clamping members are spread apart to engage a larger splicing member.
- 70 15. In a splicing tool, the combination of a pair of opposed metallic members, said metallic members being formed with opposing grooves of a size adapted to form an aperture for passing the
- 75 16. In a splicing tool, the combination of a pair of opposed metallic members, said metallic members being formed with opposing grooves of a size adapted to form an aperture for passing the

conductor to be spliced, said grooves communicating on one side with a trough in each clamping member and communicating on the other side with a tapered trough-like formation in each clamping member adapted to form a funnel leading to said opening, said latter trough-like formations being substantially half-frustoconical and being provided with overlapping flanges extending from an offset portion whereby the funnel is maintained closed when the clamping members are spread apart to engage a larger splicing member, said first-mentioned trough being provided with adjustable jaw members for engaging a splice.

8. In a splicing tool for high tension lines, the 15 combination of an elongated insulating pole with

5 a splicing tool carried by said pole, said splicing tool comprising a pair of movably mounted levers carried by said pole, a jaw mounted on each of said levers for limited universal movement, each 10 of said jaws opposing each other, and each of said jaws being recessed to receive an automatic splice, resilient means for moving the jaws in one direction, and threaded means actuated by said pole for moving the jaws in the opposite direction, said jaws being formed with tapered guide members providing a tapered recess in the open end of said jaws when a splice is gripped by said jaws for guidance of a conductor into a splice held by said jaws.

DAVID C. HUBBARD.
